(57) **CLAIM**

The ornamental design for a pressure cooker, as shown and
described.

DESCRIPTION

The patent or application file contains at least one drawing
executed in color. Copies of this patent or patent application
publication with color drawing(s) will be provided by the
Office upon request and payment of the necessary fee.

1. Pressure cooker

1.1: Front

1.2 Back

1.3: Left

1.4: Right

1.5: Top

1.6: Bottom

1.7: Perspective

The portion of the design shown in the color red is for the
purpose of illustrating portions of the pressure cooker and
forms no part of the claimed design.

1 Claim, 7 Drawing Sheets
